UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

STEEL-CAR CONSTRUCTION.

No. 884,825.

Specification of Letters Patent. Patented April 7, 1908.

Original application filed July 6, 1904, Serial No. 215,492. Divided and this application filed December 5, 1906. Serial No. 346,439.

To all whom it may concern:

Be it known that I, ETHAN I. DODDS, a citizen of the United States, residing at Pullman, in the county of Cook and State of Illinois, have invented certain new and useful Improvements in Steel-Car Constructions, of which the following is a specification.

This invention relates to steel car constructions, and the present application constitutes a division of an application heretofore filed by me on the 6th day of July, 1904, Serial No. 215,492.

The present invention pertains more specifically to a novel and improved form of steel car-body, the main purpose of which is to facilitate the discharge of the load by means of hinged doors which constitute, when closed, the load-supporting bottom of the body. The leading structural feature of the body consists in giving to both the side and end walls a downwardly divergent inclination, which affords a large opening for the discharge of the load, and obviates any tendency of the load to stick or adhere to the side or end walls in discharging. Preferably, and as herein shown, the side walls are straight, while the end walls are of a generally rounded form to afford the maximum load capacity possible without interference with the trucks in discharging. Preferably, and as herein shown, each end wall is made up of a plurality of straight sections disposed at an angle to each other and tapered along their lines of junction with each other and with the side walls, conformably to the general scheme of downwardly diverging walls throughout the body. In the preferred arrangement of hinged doors forming the bottom, as herein shown, I provide a pair of side doors which are hinged to the lower margins of the side walls of the body, and a pair of end doors disposed and operating at right angles to said side doors and hinged to the lower margin of the intermediate sections of the end walls of the body.

The invention will be readily understood when considered in connection with the accompanying drawings, wherein,—

Figure 1 is a top plan view of my improved car-body, with the underframe supporting the same also appearing in skeleton outline; Fig. 2 is a side elevation of Fig. 1; Figs. 3 and 4 are enlarged cross-sectional views on the

lines 3—3 and 4—4, respectively, of Fig. 1, viewed in the directions indicated by the arrows.

Referring to the drawings, 5 may designate as an entirety the skeleton of a steel underframe, and 6 the trucks on which the same is mounted, which parts may be of any ordinary or usual construction and form only co-operating features in their relation to the present invention. 7 may designate the side sills, and 8 the center sills of the underframe, on which the car-body is supported and braced in the manner hereinafter described.

The car-body itself is made up of a pair of oppositely disposed side walls 9 that are suitably secured to and within the side sills 7, and are so inclined as to be downwardly divergent relatively to each other, and a pair of similarly inclined end walls, each of which is made up of an intermediate section 10 and side sections 11, said intermediate and side sections being suitably beveled and mitered to form proper joints or connections with each other and with the side walls, as clearly indicated in Fig. 1.

The joints at the junctions of the end and side walls, as well as those at the junctions of the sections of the end walls, are preferably formed by angle-bars riveted to the walls and to each other, as indicated in the drawings and in a manner well understood in the art, this detail of construction forming no feature of the present invention. The end walls are supported, through the intermediate sections 10, on the center sills 8 which pass therethrough, as best shown in Figs. 1 and 4, and are braced by struts 12 connecting said intermediate sections 10 with the center sills 8 outside the body.

The bottom of the car-body is made up of a series of doors hinged thereto; the preferred arrangement herein shown comprising a pair of oppositely disposed side doors 13 that are hinged at 14 to the lower edges of the side walls 9, and a pair of oppositely disposed end doors 14 arranged and operating at a right angle to the doors 13, and hinged at 15 to the lower edges of the intermediate sections 10 of the end walls. As a convenient means for raising and lowering said doors, I have shown a central longitudinal shaft 16 journaled on across and between the end

walls, with chains or cables 17 and 18 depending therefrom and connected to the inner or free margins of the doors 13 and 14, respectively. The shaft 16 is provided with the usual hand wheel 19 and pawl and ratchet 20 for operating and locking the same.

From the foregoing it will be seen that my present invention provides a car-body not only of considerably greater area at its bottom than at its top, but also opening throughout the entire extent of its bottom for the automatic discharge of the load, and further provided with downwardly and outwardly inclined walls all around, which prevents the adherence of any part of the load to such side walls and insures a clean discharge of the entire contents of the body.

I am aware that car-bodies having dumping bottoms and upright walls in part outwardly inclined from top to bottom to facilitate discharge have been proposed; but so far as I am aware my present design affords the first instance of a car-body of this type wherein the downward divergence of the upright walls is applied throughout the entire extent of the latter.

I claim:

1. In a steel car construction, a car-body having downwardly divergent straight side walls, downwardly divergent rounded end walls, and a hinged bottom, substantially as described.

2. In a steel car construction, a car-body having downwardly divergent side and

rounded end walls, and a bottom comprised wholly of a plurality of hinged doors, substantially as described.

3. In a steel car construction, a car-body having downwardly divergent straight side walls, downwardly divergent rounded end walls, a pair of doors hinged to the lower edges of said side walls, and another pair of doors hinged to the lower edges of said end walls, said doors unitedly making up the bottom of the car-body, substantially as described.

4. In a steel car construction, a car-body having downwardly divergent straight side walls, and downwardly divergent rounded end walls, each of the latter comprising a plurality of tapered sections marginally united to each other and to the ends of said side sills, substantially as described.

5. In a steel car construction, a car-body comprising downwardly divergent straight side walls, downwardly divergent rounded end walls, each of the latter including an intermediate and end sections tapered and marginally united to each other and to the ends of said side walls, and a dumping bottom formed by doors hinged to the lower edges of said side walls and to the lower edges of the intermediate sections of said end walls, substantially as described.

ETHAN I. DODDS.
